UNITED STATES PATENT OFFICE.

ORRA L. GILLILAND, OF ORTLEY, SOUTH DAKOTA.

SHOCK-LOADER.

1,076,670.

Specification of Letters Patent.

Patented Oct. 28, 1913.

Application filed July 7, 1911, Serial No. 637,327. Renewed August 30, 1913. Serial No. 737,520.

To all whom it may concern:

Be it known that I, ORRA L. GILLILAND, a citizen of the United States, residing at Ortley, in the county of Roberts and State of South Dakota, have invented certain new and useful Improvements in Shock-Loaders; and I do hereby declare the following to be a full, clear, and exact description of the invention, such as will enable others skilled in the art to which it appertains to make and use the same.

My invention has for its object to provide an improved shock loader so-called, to-wit, a machine adapted to pick up shocks of grain, bundles of grain, or even loose grain and deposit the same in a receptacle, preferably, a wagon driven along at the side of the machine.

Generally stated, the invention consists of the novel devices and combinations of devices hereinafter described and defined in the claims.

The improved shock loader is illustrated in the accompanying drawings wherein like characters indicate like parts throughout the several views.

Referring to the drawings, Figure 1 is a plan view of the machine, some parts thereof being removed; Fig. 1^a is a detail in section on the line $x^a x^a$ of Fig. 1; Fig. 2 is a side elevation of the machine; Fig. 3 is a rear elevation of the machine; Fig. 4 is a vertical section taken on the line $x^4 x^4$ of Fig. 1, some parts being broken away; Fig. 5 is a transverse vertical section taken on the line $x^5 x^5$ of Fig. 1; Fig. 6 is a detail in section taken on the line $x^6 x^6$ of Fig. 5; Fig. 7 is a plan view of one of the so-called bundle gathering devices, some parts being broken away; Fig. 8 is a side elevation of the parts shown in Fig. 7, some parts being indicated by dotted lines; Fig. 9 is a diagrammatic detail showing certain driving connections found in the vicinity of the line marked $x^9 x^9$ on Fig. 1; Fig. 10 is a diagrammatic detail illustrating driving connections shown in the vicinity of the line marked $x^{10} x^{10}$ on Fig. 1; and Fig. 11 is a transverse section on the line $x-x$ of Fig. 1, some parts being removed.

The machine comprises a main truck frame 1 and supplemental or gathering frames 2, the projecting front end side portions of the former being connected to the rear end portions of the latter by hinges 3. (See Figs. 2 and 8.)

The main truck frame 1 is supported by rear traction wheels 4 and front steering wheels 5. The said traction wheels 4 are connected in the usual way to the ends of a rear axle 6 that is journaled in suitable bearings on the rear portion of the frame 1. The steering wheels 5 are loosely journaled on the ends of a relatively short front axle 7 that is intermediately pivoted to an overlying short bolster 8 rigidly secured to the front portion of the said frame 1.

The supplemental or gathering frames 2 are laterally spaced and extended vertically and longitudinally of the machine and their front end portions are carried on caster wheels 9 (see Figs. 2 and 8). The lower plates of the gathering frames 2 are forwardly extended and upwardly curved so that they will not catch in the ground even if brought into contact with irregular ground. The caster wheels 9 permit the front end portions of the gathering frames to follow the course of the machine with a little lateral resistance.

Working between the two laterally spaced forwardly projecting gathering frames 2 is a gathering deck preferably in the form of a fork or slatted structure 10, which, at its rear end portion, is pivotally connected to the laterally spaced forwardly projecting portions of the main frame 1, by a transverse hinge slot 11 (see Figs. 1, 2 and 4). At its rear end portion, the fork 10 is provided with rearwardly and upwardly projecting laterally spaced lifting arms 12, the ends of which are attached to the front ends of fork lifting cables 13. These cables 13, as shown, pass under idle guide sheaves 14 mounted on a transverse rod 15 secured to the main frame 1. The rear ends of the said cables 13 are attached to and adapted to be wound upon small windlass drums 16 secured to a transverse windlass shaft 17 journaled in suitable bearings 18 as shown, secured on a rearwardly projecting operator's platform 19 which, in turn, is rigidly secured to the main frame 1. When the cables 13 are drawn upon, the front end of the gathering fork 10 will be raised, and conversely, when the cables are slackened, the front end of the said fork will be lowered into position to pick up from the ground, shocks, or bundles of grain or even loose grain. For holding the fork in an inoperative position, an ordinary latch segment 20

(see Figs. 1 and 3) is secured to one of the bearings 18, and the windless shaft 17 is provided with a latch lever 21 for coöperation of the said segment.

5 Journaled in each gathering frame 2 at the front and rear thereof are approximately vertical sprocket shafts 22 that carry upper and lower sprockets 23. Sprocket chains 24 run over the coöperating upper and lower sprockets 23, and these sprocket chains carry outwardly projecting approximately vertical gathering blades 25 that are braced from the links thereof so that they will always stand approximately at the right angle to the links to which they are attached. As shown in Figs. 7 and 8, the gathering blades 25 are pivotally attached at their inner edges to vertical slats 26 secured to certain of the flanges of the upper and lower coöperating chains 23, and to brace the same without destroying the flexibility of said chains, oblique upper and lower bracing links 27 are pivoted to the said blades 25 and the adjacent slats 28 secured to other links of said upper and lower coöperating chains. The lower ends of the rear sprocket shafts 22 carry beveled gears 29 that mesh with beveled gears 30 carried by short approximately horizontal shafts 31 journaled in suitable bearings 32 secured on the bottom of the gathering frames 2. The rear ends of these short shafts 31 are connected by knuckle joints 33 to the front ends of driving shafts 34 journaled in suitable bearings on the frame 1 and provided at the rear ends with beveled gears 35 (see Figs. 1 and 2). The beveled gears 35 mesh with bevel gears 36 carried by the outer ends of the transverse shaft 37 journaled in suitable bearings on the frame 1. At its intermediate portion, the transverse shaft 37 is provided with a sprocket 38 (see Figs. 1 and 4) over which and a larger sprocket 39 on the rear axle 6 runs a sprocket chain 40. The sprocket 39 is loosely journaled on the rear axle 6 but is held against lateral movements and carries a half clutch 42 (see particularly Figs. 1 and 5). The half clutch 42 is adapted to be engaged by a coöperating half clutch 41 that is mounted to slide upon but is carried with the rear axle 6. The engagement of the half clutch 41 with the half clutch 42 and the disengagement therefrom, so as to couple the axle 6 to the shaft 37, and to disconnect the same therefrom, at will, is as shown, accomplished by means of a shipper lever 43 (see Figs. 1 and 6), which is intermediately pivoted to a transverse bar 44 of the main frame 1 with its free end working in a groove of the half clutch 41.

Extending rearward and slightly upward from the gathering fork 10 with its lower front portion positioned to receive from the rear portion of the said fork, is an endless

slat and belt conveyer, as shown, made up of sprocket chains 44 and toothed slats 45. These chains 44 run over small sprockets 46 (see Figs. 1 and 4) carried by transverse shafts 47 mounted in suitable bearings on the projecting side portions of the main frame 1. The upper shaft 47 projects at one end and is provided with a sprocket 48 (see Figs. 1 and 9). A sprocket chain 49 runs over the sprocket 48 and over a sprocket 50 on a transverse countershaft 51 journaled in suitable bearings on the frame 1. The counter shaft 51 is provided with a spur gear 52 that meshes with the spur gear 53 carried by the counter shaft 37, already noted. The shaft 51 and connections between the same and the shafts 37 and 47 serve to drive the inclined carrier belt 44-45 in the proper direction.

Side boards 54 are, as shown, rigidly secured to the oblique side bars 1^a of the frame 1 just outside of the carrier or conveyer belt 44-45. Also it may be here noted that the elevator shafts or rollers 47 are journaled in the ends of these oblique bars 1^a. The endless conveyer 44-45 projects over and is arranged to deliver the bundles or grain onto the receiving portion of a transversely extended and movable endless elevator belt shown, as preferred, as made of endless sprocket chains 55 and transverse toothed slides 56 (see particularly Figs. 1 and 5). That portion of the elevator belt which extends across the rear portion of the machine frame 1 is horizontally disposed and that portion thereof which projects at one side of the said frame is obliquely extended upward, preferably at an angle of about 30 degrees. At its receiving and delivery portions, respectively, the sprocket chain 55 runs over small sprockets 57 and 58 of sprocket shafts 59-60. The shaft 59 is journaled in suitable bearings on a superstructure 1^b formed as part of the rear portion of the frame 1 and supporting a transverse stop board 61 at the rear of the horizontal portion of the said elevator belt 55-56. The shaft 60 is journaled in suitable bearings on the upper end portion of an oblique frame extension 62, the front and rear sides of which project high above said elevator belt so as to confine the bundles and hold the same subject to the said elevator belt. This frame extension 62, at its lower end, is rigidly secured to the frame superstructure 1^b. The intermediate lower runs of the chains 55 run under idle guide sprockets 63 of an idle shaft 64 (see Figs. 1, 4 and 5), journaled in suitable bearings on the frame superstructure 1^b. The intermediate portions of the upper runs of the said chains 55 run under idle guide wheels 65 journaled to longitudinally spaced upwardly extended portions of the frame superstructure 1^b.

The sprocket shaft 58, at its front end is provided with a sprocket 66 and the intermediate sprocket shaft 64 is provided at its front end with two sprockets 67—68. The sprocket chain 69 runs over the sprockets 66—67. A short sprocket chain 70 runs over the sprocket 68 and over a sprocket 71 carried by a counter shaft 72 journaled in suitable bearings on the frame 1. At its front end, the shaft 72 is provided with a small beveled gear 73 that meshes with a bevel gear 74 carried by the shaft 37, before noted, (see Figs. 1 and 10). These connections serve to drive the elevator belt in the proper direction from the counter shaft 37.

The machine is steered by manipulation of a hand wheel 75 secured to the upper end of a steering post 76 (see Figs. 1, 2 and 3), mounted in suitable bearings on the frame 1 and superstructure 1^b and provided at its lower end with a worm 77. The worm 77 engages a worm gear 78 secured on the rear end of the rod 79 mounted in suitable bearings on the frame structure 1. At its front end, the shaft 79 is provided with a worm 80 that meshes with a worm gear 81 secured on one end of a short windlass shaft 82 (see Fig. 1) mounted in suitable bearings on the frame 1. The shaft 82 carries a windlass drum 83. A steering cable 84 is secured to and wound upon the drum 83, and its ends are attached to the front axle 7 at points on opposite sides of its pivotal connection to the bolster 8.

The side members of the gathering fork or deck 10, to which the lifting arms 12 are secured, see Figs. 1 and 1^a are provided with outwardly extended yokes 12^a that embrace adjacent parallel bars a^1 , the front ends of which are rigidly secured to the base or lower portions of the gathering frames 2. These yokes permit the required limited vertical movements of the gathering fork and cause the fork to serve as a brace to tie the gathering frames together against lateral separation.

In the main views of the drawings, the gathering frames are shown as set in vertical positions and they are operative in such positions, but preferably, they are inclined inward toward their tops, as shown in Fig. 11, by reference to which, it will be noted, that the gathering plates or arms 25 are set at such angles in respect to the inclined gathering frames that they will be horizontally disposed when moved over the gathering fork 12. When the gathering plates 25 are moved at the rear of the gathering frames 60 and backward along their outer sides, they are turned upward at steep angles, so that they will readily clear the various other parts of the machine.

This improved machine may be propelled 65 or driven forward either by an explosive

engine carried on the framework thereof, and having suitable connections to the rear axle or in any other transverse shaft, or it may be drawn by horses attached thereto in any of the well known ways.

70

Under forward movement of the machine, the shocks, bundles or loose grain will be picked up by the fork 10 and will be forced rearward on the said fork by the alternate actions of the gathering blades or arms 25 of the gathering heads and will be delivered to the receiving lower portion of the endless inclined carrier 44—45. By the latter, they will be delivered onto the horizontal receiving portion of the elevator belt 55—56 and by this elevator belt will be raised and then dropped onto the wagon or receptacle which is moved at the side of the machine. When the machine is out of action and simply driven or moved from place to place, the fork may be raised by manipulation of the lever 21, and all the running parts of the machine thrown out of action by manipulation of the shipper lever 43.

75

80

85

90

What I claim is:

1. In a machine of the kind described, the combination with a wheel truck, of a pair of laterally spaced gathering devices carried in front thereof, a gathering fork adjustable vertically between and in respect to said gathering devices, means for delivering the bundles or grain rearward from said fork.

95

2. In a machine of the kind described, the combination with a wheel truck, of a pair of laterally spaced gathering devices carried in front thereof, a gathering fork adjustable vertically between and in respect to said gathering devices, means for delivering the bundles or grain rearward from said fork, and means for carrying the bundles transversely of the machine and elevating the same for delivery at one side of the machine.

100

3. In a machine of the kind described, the combination with a wheel truck, of a pair of laterally spaced gathering devices including driven chains with gathering blades, working in front of said truck, a gathering fork adjustable vertically between and in respect to said gathering devices, an endless driven carrier for delivering the bundles rearward from said fork, and a transversely movable endless elevator belt receiving the bundles from the said endless carrier and delivering the same at one side of the machine.

105

4. In a machine of the kind described, the combination with a wheel truck, of a pair of laterally spaced gathering devices including driven chains with gathering blades, working in front of said truck, a gathering fork adjustable vertically between and in respect to said gathering devices, an endless driven carrier for delivering the bundles rearward from said fork and a transversely movable endless elevator belt receiving the bundles from the said endless carrier and delivering the same at one side of the machine.

110

115

120

125

130

the same at one side of the machine, and means for vertically moving the front portion of said gathering fork.

5. In a machine of the kind described, the combination with a truck having traction wheels and steering wheels, of laterally spaced gathering frames having their rear portions connected by hinges to the front portion of the said truck frame, wheels supporting the front portions of said gathering frames, endless chains and driving means therefor mounted on said gathering frames and provided with projecting gathering blades, a gathering fork adjustable vertically between and in respect to said gathering frames, and means for vertically moving said gathering fork.
- 10 6. In a machine of the kind described, the combination with a truck having traction wheels and steering wheels and means for

controlling said steering wheels, the said steering wheels being located in front of said traction wheels, of laterally spaced gathering frames connected at the rear portions by hinges to the front portions of said gathering frames, wheels supporting said gathering frames, driven gathering devices mounted on said gathering frames, a fork pivotally mounted to work between said gathering frames, means for vertically adjusting said fork in respect to said gathering frames, and means for picking up the bundles from the ground and for carrying the same rearward.

25 In testimony whereof I affix my signature in presence of two witnesses.

ORRA L. GILLILAND.
